CLAIM

The ornamental design for an elbow component for respiratory mask, as shown and described.

DESCRIPTION

FIG. 1 is a perspective view of an elbow component for respiratory mask according to a first embodiment of our design;

FIG. 2 is a front view thereof;

FIG. 3 is a rear view thereof;

FIG. 4 is a top view thereof;

FIG. 5 is a bottom view thereof;

FIG. 6 is a left side view thereof with the right side view thereof being a mirror image thereof;

FIG. 7 is a perspective view of an elbow component for respiratory mask according to a second embodiment of our design;

FIG. 8 is a front view thereof;

FIG. 9 is a rear view thereof;

FIG. 10 is a top view thereof;

FIG. 11 is a bottom view thereof; and,

FIG. 12 is a left side view thereof with the right side view thereof being a mirror image thereof.

The broken lines in the drawings illustrate portions of the elbow component for respiratory mask that form no part of the claimed design.

Stippling and line shading have been used in the drawings to indicate a contrast in appearance.
